MATERIAL GATHERING AND LOADING
MACHINE

Robert H. Kraft, Chicago, Ill., assignor to Goodman Manufacturing Company, Chicago, Ill., a corporation of Illinois

Application July 31, 1933, Serial No. 682,982
Renewed August 23, 1937

22 Claims. (Cl. 198—8)

This invention relates to improvements in material gathering and loading machines particularly adapted for loading coal at the working face of a mine and has as its principal objects to provide a simple and efficient gathering mechanism for a machine of the class described including a pair of endless chains extending along each side of an elevating conveyer and forwardly of the forward end thereof for gathering material in advance of the conveyer along the ground and depositing it thereon.

Other objects of my invention are to provide a novel form and arrangement of gathering arms which will hold the gathering mechanism in engagement with the ground during the loading operation, and also to provide a means to prevent the gathering arms from carrying material laterally beyond the conveyer at their outward turning point away from the conveyer.

Other objects of my invention will appear from time to time as the following specification proceeds.

My invention may best be understood with reference to the accompanying drawings wherein:

Figure 1 is a fragmentary perspective view of a loading machine illustrating one form in which my invention may be embodied;

Figure 2 is a plan view of the device shown in Figure 1;

Figure 3 is an enlarged side elevation of the forward portion of the device shown in Figure 2 with parts broken away and in section to more clearly show the details of my invention;

Figure 4 is an enlarged partial fragmentary vertical transverse sectional view looking towards the rear end of the machine showing certain details of the support and drive to the front conveyer; and

Figure 5 is an enlarged partial fragmentary sectional view looking towards the rear end of the machine taken through the drive mechanism for the gathering element.

Referring now in particular to the drawings illustrating one form in which my invention may be embodied, a truck or main frame 10 is provided which, as herein shown, is carried on laterally spaced continuous tread devices 11, 11. A gathering and loading element, generally indicated by reference character 12, is mounted on the forward end of said main frame and extends forwardly and downwardly therefrom, at an incline, towards the ground and is adjustable with respect to the ground about a horizontal transverse axis disposed adjacent its rear end. A discharge conveyer 13 is carried on the main frame

10. Said discharge conveyer is horizontally adjustable about a vertical axis disposed adjacent its forward end and is vertically adjustable with respect thereto about a horizontal transverse axis. Said discharge conveyer extends from a point disposed beneath the discharge end of the gathering and loading element 12 beyond said main frame for discharging material into suitable receptacles, such as mine cars.

A suitable means is provided for affording a source of power for driving the gathering and loading element 12; for vertically adjusting said gathering and loading element with respect to the mine bottom; for driving the laterally spaced continuous tread devices 11; and for driving the discharge conveyer 13 and adjusting said discharge conveyer with respect to the main frame 10 about both vertical and horizontal axes which, as herein shown, includes a pair of motors 14, 14 of an ordinary electrical type. Each of said motors is suitably secured to one side of the main frame 10 and is disposed between the top and bottom runs of each laterally spaced continuous tread device 11 and extends laterally from said main frame and continuous tread devices. The axes of rotation of said motors extend transversely of the main frame 10, and said axes are herein shown as being coaxial. Each of said motors is provided with a suitable motor pinion which meshes with and drives a spur gear 16. The spur gears 16, 16 are keyed on opposite ends of a transversely extending shaft 17, which shaft forms a common drive member for effecting operation of the machine through a novel arrangement of drive gearing. Said gearing arrangement has been clearly described in Patent No. 2,024,458 which issued on December 17, 1935 and was divided from this application, so will only herein be described in so far as is necessary to make my present invention readily understandable.

With reference now in particular to the details of the gathering and loading element 12 and several of the novel features of my invention, brackets 45, 45 extend upwardly from opposite sides of the main frame 10 adjacent the forward end thereof and are secured thereto. An inclined conveyer frame 46 is carried between said brackets on a transverse shaft 47 for pivotal movement with respect to said main frame. A conveyer frame 48 is secured between the brackets 45, 45 and extends rearwardly from said inclined conveyer frame in a horizontal direction.

The conveyer frames 46 and 48 together form a guide frame for a suitable conveying means for elevating material and discharging it into the

discharge conveyer 13, which may be of any type well known to those skilled in the art but is herein preferably shown as being a flight conveyer 49. Said flight conveyer comprises a pair of 5 endless chains 50, 50 having flights 52, 52 carried therebetween. Said endless chains extend downwardly along the lower side of said conveyer frame and are trained around sprockets 53, 53 keyed on a transversely extending shaft 54 disposed adjacent the forward end of said inclined conveyer frame. From said sprockets, said chains extend upwardly along the top surface of a plate 55 extending along said inclined conveyer frame and forming a bottom for the conveyer and along a plate 56 forming a bottom for the conveyer frame 48, to and around suitable drive sprockets keyed to a shaft 57 at the rear end of said last-mentioned conveyer frame.

The forward end of the gathering element rests 20 on the ground on a shoe 59 which extends laterally across and beyond the sides of the forward portion of the conveyer frame 46.

The gathering head includes an inclined apron 60 which is mounted on the upper side of the 25 forward portion of the conveyer frame 46 and extends laterally beyond the sides thereof and rearwardly therealong from the forward end of the shoe 59. Said apron has a discharge edge extending across the forward end of the flight conveyer 49, and extends along opposite sides of said conveyer to form a support for a pair of elongated chain guides 61, 61. Said chain guides are secured to the upper side of said inclined apron and extend downwardly along opposite sides of 35 said conveyer and forwardly beyond the forward end of said apron a substantial distance.

The apron 60, as herein shown, is parallel to the conveyer 49 and the chain guides 61, 61 extend in parallel relation with respect to said 40 apron to a point adjacent the forward end thereof where they extend beyond the forward end of said apron and curve to a plane which is substantially parallel with the ground when the shoe 59 engages the ground.

45 The chain guides 61, 61 are of an ordinary construction and each includes a top plate 62 and a bottom plate 63. Said plates are joined together by spacing members 64, 64. A guide groove is thus formed between said top and bottom plates and the outer periphery of said spacing members, which is adapted to receive and guide an endless chain 65 for movement therealong. The forward and rear portions of said chain guides are herein shown as being separated so said portions may be adjustably secured to the apron 60 to permit slack in the chain 65, to be taken up as said chain wears (see Fig. 1).

The endless chains 65, 65 are driven from the flight conveyer 49 in the following manner: 60 Sprockets 81, 81 are secured to the upper end of shafts 82, journaled within housings 83, 83 secured to the underside of the apron 60 in a suitable manner. Said shafts extend substantially perpendicular to the inclined apron 60 and are 65 driven at a slower rate of speed than the speed of the flight conveyer 49 to permit said flight conveyer to carry material away from the gathering arms 69, 69 as it is delivered thereon. Worm gears 84, 84 are secured to said shafts and are 70 meshed with and driven from worms 85, 85 disposed adjacent opposite ends of the transversely extending shaft 54 which is driven from the sprockets 53, 53 and endless chains 50, 50 in an obvious manner.

75 The gathering means for picking up material

from the ground and depositing it onto the flight conveyer 49 includes a plurality of laterally extending spaced apart gathering arms 69, 69 pivotally connected to lugs 67, 67 extending outwardly from certain spaced links or blocks 66, 66 of said chain.

Said gathering arms are restrained from pivotal movement at their outward turning points away from the conveyer by means of pairs of parallel spaced links 71, 71. Each pair of said links is pivotally connected to opposite sides of a lug 70 projecting rearwardly from each gathering arm. Said links extend rearwardly and inwardly from their respective lug 70 and are pivotally connected at their opposite ends to a block 73 of said chain. As herein shown, said block is a second link of the chain rearwardly from the link 66 to which the gathering arm 69 is connected.

Said gathering arms are aided in clearing material on the conveyer, and the gathering mechanism is held to the ground, by means of the form of the forward engaging face thereof. Said forward face is indicated by reference character 74 and is inclined upwardly away from the direction of travel of the gathering arm, or towards the rearward upper end thereof.

A plurality of bits 75, 75 of the ordinary pick point type, similar to those used in mining machine cutter chains, project from the outer ends 3 of the gathering arms 69, 69 and are detachably secured thereto by means of suitable set screws. Said bits serve to permit the machine to free itself when the coal is tight, and cut under the coal where it has not broken down, and also serve 24 to break up and dislodge large lumps of coal when necessary.

The gathering arms 69, 69 on opposite chain guides 61, 61 are alternately arranged and said gathering arms and chain guides are so arranged with respect to the apron 60 and conveyer 49 that the outer ends of said gathering arms move longitudinally towards said conveyer along said apron in a path which substantially coincides with the longitudinal center line of said conveyer. This arrangement of gathering arms prevents fouling of large lumps of material between opposite gathering arms, and with the upwardly and rearwardly inclined faces of said gathering arms enables said gathering arms to more readily clear material deposited on said conveyer at their outward turning points.

It may be seen from the foregoing that since the chain guides 61, 61 extend along the ground beyond the apron 60 in a plane substantially parallel to the ground, when the shoe 59 is in engagement with the ground, that the gathering arms 69, 69 may pick up material from the mine bottom directly in front of said apron and thus clear a path in the coal for said apron. It may also be seen that the upwardly and rearwardly inclined forward engaging faces 74 of the gathering arms 69 tend to hold said gathering arms to the ground when gathering loose material which prevents climbing of the entire gathering mechanism in the coal during the loading operation.

Referring now in particular to the novel means which cooperate with the inclined forward faces of the gathering arms 69, 69 to deflect material onto the conveyer 49 as said gathering arms turn 70 away therefrom, a pair of deflecting plates 76, 76 is provided. Each of said deflecting plates is spaced above the apron 60 a distance sufficient to permit a gathering flight 69 to pass therethrough. Said plates with said apron form passageways 75

opening to the side of the conveyer 49 at the outward turning point of the gathering arms 69, 69, which extend away from said conveyer and forwardly and laterally along the retreating side of each chain guide 61. The portions of the deflecting plates 76, 76 which extend beyond the chain guides 61, 61 are flared upwardly to deflect material which may fall from the coal face onto said plates into the conveyer. Said deflecting plates are secured to the rearward and outer sides of the chain guides 61, 61 by means of a pair of brackets, generally indicated by reference character 71, which are secured to the rear end and outer side of each chain guide, and a pair of brackets 79, 79 suitably secured to and projecting upwardly from the outer sides of said apron.

Auxiliary deflecting members 80, 80 are provided which extend rearwardly of the deflecting plates 76, 76 along the sides of the conveyer 49 for collecting any loose material which falls thereon or may be thrown thereon by the gathering arms and deflecting said material onto said conveyer.

It may be seen from the foregoing that the links 71, 71 pivotally connected between the lugs 70, 70 and blocks 73, 73 of the chains 65, 65 serve to initially retard angular swinging movement of said gathering arms as they move away from the conveyer 49, and hold the angle of each gathering arm as it approaches the engaging surface of the deflecting plate 76 in such a position as to deflect large lumps of material onto the conveyer and prevent crushing of said lumps between said gathering arms and the inner ends of said deflecting plate. It may also be seen that said links position said gathering arms 69, 69 at their forward turning point along the ground, so they may efficiently gather material from the front end of said apron and prevent scattering of coal in front of said gathering and loading element by retarding angular movement of said arms away from the conveyer when they first engage the loose material and then accelerating said arms to move the loose material onto said apron.

While I have herein shown and described one form in which my invention may be embodied, it will be understood that the construction thereof and the arrangement of the various parts may be altered without departing from the spirit and scope thereof. Furthermore, I do not wish to be construed as limiting myself to the specific embodiment illustrated, excepting as it may be limited in the appended claims.

I claim as my invention:

1. In a loading machine, an orbitally guided endless chain, a gathering arm pivotally mounted on a link of said chain, said gathering arm having a forward face inclined towards the rearward end thereof, means pivoted to the rearward side of said gathering arm having pivotal connection with another of the links of said chain for limiting rearward movement of said gathering arm and delaying the turning action thereof, and a deflecting member cooperating with the inclined face of said gathering arm for deflecting material away from said gathering arm.

2. A loading machine in accordance with claim 1 wherein the deflecting member is spaced above the gathering arm.

3. A loading machine in accordance with claim 1 wherein the link to which said supporting means is connected is the second link rearwardly from the link to which said gathering arm is connected.

4. A loading machine in accordance with claim 1 wherein the link to which said supporting means is connected is the second link rearwardly from the link to which said gathering arm is connected, and wherein the deflecting member is spaced above the endless chain and gathering arm.

5. In a loading machine, a conveyer, an apron extending forwardly therefrom and laterally beyond the sides thereof, gathering means mounted on said apron and extending along opposite sides of said conveyer including a pair of orbitally guided endless chains having spaced-apart gathering arms projecting laterally therefrom, and a deflecting shield disposed over each of said endless chains at the turning point of said arms away from the conveyer and forming a passageway between the under surfaces thereof and said apron through which said chains and gathering arms pass.

6. In a loading machine, a conveyer, an apron extending forwardly therefrom and laterally beyond the sides thereof, gathering means mounted on said apron and extending along opposite sides of said conveyer including a pair of orbitally guided endless chains having spaced-apart gathering arms projecting laterally therefrom, and a deflecting shield disposed over each of said endless chains at their turning point away from the conveyer, said deflecting shields forming a passageway between the under surface thereof and said apron, and the angles of said gathering arms with respect to said deflecting shields, as said gathering arms approach said passageways, being such that said arms coacting with said shields will deflect material onto said conveyer as they enter said passageway.

7. A loading machine comprising an inclined conveyer, an inclined apron extending forwardly therefrom and laterally beyond the sides thereof and a pair of orbitally guided endless chains having gathering arms thereon carried by said inclined apron on opposite sides of said inclined conveyer and extending along said inclined conveyer and forwardly therefrom beyond the forward end of said inclined apron in such a manner that said gathering arms may engage and slide along the ground, and a deflecting shield disposed over the rearward and retreating portion of the path of travel of each endless chain, said deflecting shield forming a passageway between its under surface and said inclined apron and extending from a point where said endless chains move away from said inclined conveyer and around to and along the outer sides of said inclined apron.

8. In a loading machine, an inclined conveyer, an inclined apron extending along each side thereof and forwardly therefrom, a pair of chain guides on said apron extending along the sides of said conveyer and forwardly along said apron beyond the forward end thereof in a plane parallel to the ground, an endless chain guided in each of said chain guides, and gathering means on said endless chains including a plurality of spaced-apart gathering arms pivotally connected to links of said chains and adapted to engage and slide along the ground forwardly of said apron, a link pivotally connected to the rearward end of each of said gathering arms and extending angularly rearwardly therefrom towards said chain and having pivotal connection with other links of said chains for limiting pivotal movement of said gathering arms and delaying the turning action thereof when turning away from

- said conveyer, bits on the ends of said gathering arms adapted to engage and cut through material on the ground, and said gathering arms having forward faces inclined towards the rearward end thereof to coat with loose material on the ground and aid in holding said arms in engagement with the ground.
9. In a loading machine, a gathering and loading element comprising an inclined endless conveyer, an elongated chain guide disposed to one side of said conveyer, an endless chain guided for movement in an orbital path along said elongated chain guide, a gathering arm pivoted to one link of said endless chain and adapted to overlap said conveyer, a supporting member pivoted to the rearward end of said gathering arm and having pivotal connection with another of the links of said inclined endless chain, said supporting member acting as a means to retard movement of said gathering arm as said chain is moved in an arcuate path around said elongated chain guide away from said conveyer, and a deflecting member extending laterally away from said conveyer from the point where said gathering arm turns away from said inclined endless conveyer, and cooperating with said gathering arm for deflecting material on to said conveyer as said gathering arm approaches said deflecting member.
10. A loading machine in accordance with claim 9 wherein the deflecting member is spaced above the gathering arm.
11. A loading machine in accordance with claim 9 wherein the gathering arm is provided with a relatively wide forward face inclined towards the rearward end thereof and wherein the deflecting member is spaced above the gathering arm for cooperation with the inclined forward face of said gathering arm and deflecting lumps of material on to said conveyer.
12. In a loading machine, a gathering and loading element comprising an inclined endless conveyer, an inclined apron extending forwardly of and laterally beyond the sides of said inclined conveyer, an elongated chain guide extending along said apron beyond the forward end thereof, an endless chain guided for movement in a closed path along said chain guide, said path extending forwardly of said inclined conveyer and thence rearwardly to and along said inclined conveyer to a point beyond the discharge edge of said apron onto said conveyer from whence said chain moves in an arcuate path away from said inclined conveyer, a plurality of gathering arms on said endless chain, and a deflecting member disposed above said guide and extending rearwardly of the rear portion of said chain guide adjacent the point where said chain moves away from said conveyer and cooperating with said gathering arms for deflecting material on to said conveyer as said gathering arms approach said deflecting member.
13. A loading machine in accordance with claim 12 wherein the under surface of said deflecting member forms a passageway between it and said apron in which said gathering arms travel.
14. A loading machine in accordance with claim 12 wherein the gathering arms are pivoted to the endless chain, and wherein means are provided to retard angular movement of said gathering arms as they approach said deflecting member so the angle of said gathering arms with respect to said deflecting member as they
- approach said deflecting member will be such as to deflect material on to said conveyer.
15. A loading machine in accordance with claim 12 wherein the gathering arms are pivoted to the endless chain, wherein means are provided to prevent rearward movement of said gathering arms with respect to said endless chain while moving along said apron and retard angular movement of said gathering arms with respect to said deflecting member as they move 10 away from said inclined conveyer, and wherein the forward faces of said gathering arms are beveled towards their rearward end, so the angle of said gathering arms as they approach said deflecting member will be such as to deflect material 15 on to said conveyer.
16. In a loading machine, a gathering and loading element comprising an inclined endless conveyer, an elongated chain guide disposed to each side of said conveyer, each of said chain guides having an endless chain guided for orbital movement thereabout, a gathering arm pivoted to one link of each of said endless chains and adapted to overlap said conveyer, a supporting member pivoted to the rear portion of each of said gathering arms and having pivotal connection with another of the links of said endless chain, said supporting members acting as means to retard movement of the outer ends of said gathering arms as said chains are moved in an arcuate 30 path around said chain guides away from said conveyer, and deflecting members extending from points adjacent opposite sides of said inclined endless conveyer where said gathering arms turn laterally away from said inclined endless conveyer and cooperating with said gathering arms for deflecting material on to said conveyer as said gathering arms approach said deflecting members.
17. A loading machine in accordance with claim 16 wherein the deflecting members are spaced above the gathering arms.
18. A loading machine in accordance with claim 16 wherein the gathering arms are provided with relatively wide forward faces inclined 45 towards the rearward end thereof and wherein the deflecting members are spaced above the gathering arms for cooperation with the inclined forward faces of said gathering arms and deflecting lumps of material on to said conveyer.
19. In a loading machine, a gathering and loading element comprising an inclined endless conveyer, an inclined apron extending forwardly of and laterally beyond the sides of said inclined conveyer, elongated chain guides on said apron 55 and extending along opposite sides of said inclined conveyer and beyond the forward end of said apron in a substantially horizontal plane when the forward end of said apron is in engagement with the ground, endless chains guided for movement in closed paths along said chain guides, said chain guides extending from a point disposed beyond the forward end of said apron and thence rearwardly and upwardly to a point beyond the discharge edge thereof and thence in an arcuate 65 path away from said conveyer, a plurality of gathering arms on said endless chains, and deflecting members disposed above said guides and extending rearwardly from the rearward portion of said chain guides adjacent the point 70 where said chains move away from said conveyer and cooperating with said gathering arms for deflecting material on to said conveyer as said gathering arms approach said deflecting member.
20. A loading machine in accordance with claim 75

19 wherein the under surface of said deflecting members form passageways between said apron and deflecting members, in which said gathering arms travel.

19 wherein the gathering arms are pivoted to the endless chains, wherein means are provided to prevent rearward movement of said gathering arms with respect to said endless chains while moving along said apron and retard angular movement of said gathering arms with respect to said deflecting members as they move away from said inclined conveyer, and wherein the forward faces of said gathering arms are beveled towards their rearward end, so the angle of said gathering arms as they approach said deflecting members will be such as to deflect material on to said conveyer. 5

21. A loading machine in accordance with claim 5 19 wherein the gathering arms are pivoted to the endless chains and wherein means are provided for retarding angular movement of said gathering arms as they approach said deflecting members so the angle of said gathering arms with respect to said deflecting members as said gathering arms approach said deflecting members is such as to deflect material on to said conveyer. 10

22. A loading machine in accordance with claim

ROBERT H. KRAFT.
